UNITED STATES PATENT OFFICE.

GARLAND DUNLAP, OF NEW YORK, N. Y., ASSIGNOR OF ONE-HALF TO MARGARET O. JENTONS, OF CLOSTER, NEW JERSEY.

SHOE FOR ELEVATOR-GUIDES.

1,076,273.

Specification of Letters Patent.

Patented Oct. 21, 1913.

Application filed March 25, 1912. Serial No. 686,075.

To all whom it may concern:

Be it known that I, GARLAND DUNLAP, a citizen of the United States, residing at New York, in the county of New York and State of New York, have invented certain new and useful Improvements in Shoes for Elevator-Guides, of which the following is a specification.

My invention relates to shoes for elevator guides.

The objects of the invention are to provide an elevator shoe in which the actuating devices shall be exposed to view for adjustment and removal; to provide a separable bearing for the stem of the shoe so that by removing the upper half of the bearing the shoe may be removed and a new one applied in a very short space of time; to provide visible readily accessible means for quickly adjusting the throw of the shoe in either direction and to provide like means for regulating the tension of the spring without changing the devices which limit the throw of the shoe. These objects I accomplish by 25 the construction shown in the accompanying drawings, in which:

Figure 1 is a side elevation of my improved elevator shoe. Fig. 2 is a plan thereof. Fig. 3 is a perspective of the casing with its upper half removed. Fig. 4 is a perspective showing a modification.

A designates the casing formed of a lower section A', having a half bearing a' in its upper face and an upper section A² having a half bearing a² in its lower face; these two half bearings registering and forming a cylindrical shaft bearing. The two sections A', A² are provided with longitudinal flanges a³, connected by bolts a⁴. The upper section A² is provided on its upper side with two apertured guide lugs a⁵, a⁶, while the inner end of the lower section A' is provided with a longitudinally extending fulcrum bar a⁷, having a plurality of transverse apertures a⁸. The lower section A' is provided with base flanges a⁹, having apertures a¹⁰ for the bolts a¹¹, which secure the casing to the cross beams B; four of the shoes being attached to each car.

50 C indicates the shoe proper having a vertical groove c, which embraces the guide rail G, and a stem or shaft C' which slides in the bearing formed between the two sections A', A² of the casing.

55 C² is a vertical lever pivoted at its lower

end by a pivot c² to the bar a⁷ and pivoted at its middle by a pivot c³ to the inner forked end of the stem C'. The upper end of the lever C² is pivoted at c⁴ to the inner end of a sliding rod C³ mounted in the two 60 guide lugs a⁵, a⁶, and provided between said lugs with a tension spring c⁵. The tension of the spring c⁵ is regulated by means of the nuts c⁶, c⁷ mounted on the rod C³ adjacent to the inner side of lug a⁶. By adjusting these nuts c⁶, c⁷, the tension of the spring to control the movement of the shoe C inwardly or away from the guide rail G may be regulated and this is the sole function of said nuts. The tension of the spring 70 may thus be regulated without changing the length of throw of the stem and shoe. The outward movement of the shoe C toward the guide rail G is limited by the nuts c⁸, c⁹ mounted on the sliding rod C³ adjacent 75 to the outer side of lug a⁵ and the movement of the shoe C away from the rail G is limited by the nut c¹⁰ on the opposite end of the rod C³ next to the lug a⁶. In practice the nuts c⁸, c⁹ will be set so that there will 80 be a space about one sixteenth of an inch between the shoe and the guide rail and the nuts c⁶, c⁷ will be set to give the required tension to the spring c⁵. Then the nut c¹⁰ will be set to allow the required play of the 85 shoe away from the guide rail. In case the spring c⁵ should break, the nut c¹⁰ will prevent the shoe C from becoming disengaged from the guide rail, and, moreover, the spring may be readily replaced by a new 90 one without the necessity of removing the shoe and its casing or bearing. Should the shoe break or wear out, it may be readily replaced by simply removing the top section 95 or cover A² of the casing. All of the parts are exposed to view and readily accessible, and there is, therefore, no need of removing the casing or bearing to either adjust any of the parts or replace them.

Referring now to Fig. 4, the casing A is 100 in two parts A⁷, A⁸, with half bearings for the stem C' of shoe C, but the two sections are separably connected by hinge knuckles a¹⁵, a¹⁶, through which are passed the pins or bolts a¹⁷ by removing which the upper section A⁷ may be lifted and the shoe removed. From the inner end of the lower section A⁸ extend two longitudinal guide rods a¹⁸, which are in the same horizontal 105 plane. The inner end of the stem C' is pro- 110

vided with a cross head C' secured by means of a nut U and sliding on the rods a¹⁹. The free ends of the rods a¹⁹ are connected by a sliding cross bar a²⁰, between which and the 5 cross head C' are the tension springs a²¹, which may be adjusted by the nuts a²² on the extremities of the rods a¹⁹ without affecting the length of the throw of the shoe and its stem. The outward movement of the 10 shoe toward its guide rail is limited by the nuts a²³ on the rods a¹⁹ between the casing and the cross head C', and opposite movement is cushioned by the springs a²¹. As in Fig. 1, all the parts are exposed for adjustment, replacement, &c. This modified construction will in some cases prove better adapted as bottom shoes than the construction shown in Figs. 1, 2, 3. In both constructions the shoe is held from rotary 15 movement and so chattering on the guide G is prevented.

What I claim is:

1. An elevator guide shoe comprising a removable casing formed in two separable 25 sections with half bearings between them, a shoe having a stem mounted removably in said half bearings, lugs or guides on the upper section, a rod passing through said lugs or guides and a tension spring exterior to 30 the casing and encircling said rod for forcing the shoe outwardly.

2. An elevator guide shoe comprising a removable casing formed in two separable sections with half bearings between them, 35 a shoe having a stem mounted removably in said half bearings, lugs or guides on the upper section, a rod passing through said lugs or guides, a tension spring exterior to the casing and encircling said rod for forcing 40 the shoe outwardly, and adjustable means also exterior to the casing and positively limiting the outward movement of the shoe.

3. An elevator guide shoe comprising a casing or bearing, a shoe having its stem 45 sliding therein, a pivoted lever connected between its ends to the inner end of the stem, a sliding rod parallel with the stem and pivoted to the end of the lever opposite its fulcrum, guide lugs on the casing for 50 said rod, and a tension spring on the rod.

4. An elevator guide shoe comprising a casing or bearing, a shoe having a stem sliding in said bearing, a lever fulcrumed at one end and pivoted between its ends to 55 the inner end of said stem, a sliding rod pivotally connected at its inner end to the free end of said lever, guide lugs for said

rod on the casing, a tension spring on the sliding rod between the said lugs, a tension nut on the rod against which the outer end 60 of said spring bears, and a stop nut on the rod adjacent to the inner guide lug to limit the outward movement of the shoe.

5. An elevator guide shoe comprising a casing or bearing, a shoe having a stem sliding in said bearing, a lever fulcrumed at one end and pivotally connected between its ends to the inner end of said stem, a sliding rod pivotally connected at its inner end to the free end of said lever, guide lugs for said 70 rod, a tension spring on the rod between said lugs, a stop nut on the rod outside of the inner guide lug, and a second nut on the rod outside of the outer guide lug.

6. An elevator guide shoe comprising a casing or bearing, a shoe having a stem sliding in said bearing, a bar extending longitudinally from the casing and having a plurality of apertures, a lever pivoted at one end in one of said apertures, and pivotally 80 connected between its ends to the inner end of the stem, a sliding rod pivotally connected to the free end of said lever, guide lugs for the rod on the casing, a tension spring on the rod between the said guide lugs, and 85 means for positively limiting the movement of the rod through the lugs.

7. An elevator guide shoe comprising a two part separable casing or bearing, a shoe having a stem sliding between the two members of the casing, a lever fulcrumed at one end to the casing, and pivotally connected between its ends to the stem of the shoe, a sliding rod pivotally connected to the free 90 end of the lever, guide lugs for the rod on the top casing member, a tension spring on the rod between said guide lugs, and means for adjusting the play of the sliding rod in the lugs.

8. An elevator guide shoe comprising a 100 casing, a shoe having a stem sliding through the casing, an exposed spring pressing the stem outwardly, adjustable means for positively limiting the outward throw of the stem and independent means for adjusting 105 the tension of the spring without affecting the length of throw of the stem and shoe.

In testimony whereof I affix my signature in presence of two witnesses.

GARLAND DUNLAP.
